UNITED STATES PATENT OFFICE.

JOSEPH ROY, OF MONTREAL, QUEBEC, CANADA.

RANGE-STOVE.

SPECIFICATION forming part of Letters Patent No. 307,804, dated November 11, 1884.

Application filed August 5, 1882. (No model.) Patented in Canada October 31, 1881, No. 13,617.

To all whom it may concern:

Be it known that I, JOSEPH ROY, of the city of Montreal, in the Province of Quebec, in the Dominion of Canada, have invented certain new and useful Improvements in Range-Stoves; and I do hereby declare that the following is a full, clear, and exact description of the same.

This invention has for its object to combine in a range-stove two furnaces, two double ovens, 10 a single oven, and a hot-water-circulating boiler in such a manner that one furnace can be used to heat the double ovens and the other furnace to heat the single oven and the hot-water-circulating boiler, the smoke passing from the range through apertures in its bottom into an underground smoke-duct, the whole forming a rectangular block.

Figure 1 is a front elevation of my improved range-stove. Fig. 2 is a top view, a portion 20 of the top broken away to show the draft-currents by arrows. Fig. 3 is a horizontal section on line *y y*, Fig. 1. Fig. 4 is a like section on line *x x*, Fig. 1. Fig. 5 is a vertical section on line *w w*, Fig. 2. Fig. 6 is a perspective view of the hot-water section of the stove, a portion of the outer wall broken away 25 to show the flues and position of the boiler. Fig. 7 is a vertical section of the range on line *v v*, Fig. 2.

30 A is a furnace; B the top of the range provided with pot-holes, and G G' are respectively upper and lower ovens.

B' is a smoke-passage passing from furnace A laterally and entering over oven G.

35 C is a deflector between the top plate, B, and top *a* of oven G, to distribute the heat and smoke, and forms a throat in which is a damper, E, to a diving-flue, D, which descends to top *b* of lower oven, G', separated from the bottom of oven G by a horizontal flue-space, *d*, in which 40 is a deflector, C', to distribute the heat and smoke between the ovens G G'. The smoke, after entering between the ovens, passes around the end of deflector C' into a diving-flue, D', which descends to the bottom plate of the range, from which the lower oven is elevated 45 to form a flue-space, *e*, in which is a deflector, C'', around the end of which the smoke and heat pass into a diagonal duct, 22, and thence through an aperture, 5, in the bottom of the range into an underground duct, 23, and thence into chimney H.

50

J is a dead-air space between the side of the ovens G G' and the furnace A, (of which *f* is the ash-pit,) to prevent direct heat, and I is a dead-air space on the opposite side of the ovens to protect them from direct external cold.

g are dead-air spaces corresponding to the thicknesses of the diving-flues.

On the opposite side of furnace A are respectively upper and lower ovens, G² G³, and B² is the smoke-passage entering over the top *a'* of oven G².

C³ is a deflector between the top plate, B, of the range and top of oven G², to distribute the heat and smoke, and forms a throat in which is a damper, E, to a diving-flue, D², descending to top *b'* of lower oven, G³, separated from bottom of oven G² by a flue-space, *d'*, in which is a deflector, C⁴. The smoke, after entering said space between the ovens, passes around the end of deflector C⁴ into a diving-flue, D³, which descends to the bottom plate of the range, from which the lower oven is elevated, and forms a flue-space, *e'*, in which 75 is a deflector, C⁵, around which the smoke passes into a diagonal duct, 22', which joins with a duct, 17, hereinafter referred to, and thence through aperture 5' in the bottom of 80 the range, into the underground duct 23, and thence into chimney H.

J' is a dead-air space between the side of ovens G² G³ and furnace A to prevent direct heat, and I' is a dead-air space on the opposite side of the ovens to protect them from external cold.

h are dead-air spaces outside the flues at the bottom of the range.

A' is a furnace at the rear of furnace A, the backs of the two furnaces separated by the dead-air space *g* corresponding to the depth of the diving-flues.

f' is the ash-pit of furnace A'.

3 is a single oven on one side of furnace A', and corresponds in height to the two ovens G G'.

B³ is a smoke-passage laterally from furnace A' and entering over top *i* of oven 3.

C⁶ is a deflector between the top of oven 3 and top plate, B, of the range to distribute heat and smoke over the top of the oven, and to form a throat in which is a damper, E², to diving-flue D, which is common to both fur-

naces. The smoke passes down flue D, thence between ovens G G', thence into flue D', thence under the bottom of oven G', thence under the bottom of oven 3, through duct 22 to heat the 5 oven, and thence through aperture 5 into the underground duct 23 leading to chimney H.

J² is a dead-air space between furnace A' and oven 3 to prevent direct heat, and I² is a dead-air space on one side of oven 3 to protect it from direct external cold.

S² S³ are vertically-hung doors of oven 3.

At the side of furnace A', opposite to oven 3, is a dead-air space, J³, and within a rectangular walled division of the range is a hot-water-circulating boiler, 4, which is supported on two walls of a lining, 16. Over the boiler is a plate, 25, bearing on top of lining 16, which is sunk below the top plate, B, of the range to form a smoke-flue, k, which is contracted at the entrance and exit by two curved walls, 26, and divided at the entrance by a deflector, 27, to divert the smoke to opposite sides of the dome. Plate 25 over the boiler has an aperture, 7, at one end, through which rises the upper end of 20 a vertical flue-plate, 19, which at the lower end is bifurcated to connect the two walls of lining 16 and divide the space between the end of the boiler and wall of the range into two flues leading into two return-flues, 28, formed by 25 the longitudinal sides of the boiler and lining 16. At the opposite end the boiler is shorter than the lining, to allow the smoke to pass downward between the end of the boiler and division-wall m of the range into horizontal 30 return-flue 8 under the boiler, and below flue 8 is a horizontal return-flue, 17, formed by the 35 walls of the lining 16, and a horizontal division-plate, 9, said flue 17 leading to aperture 5', through which the smoke passes into under- 40 ground duct 23 to chimney H.

18 is a damper in flue 17, to be closed when the boiler is not required to be heated. By closing dampers 18 and E, when furnace A is not used, all the heat from furnace A' will pass 45 over oven 3, thence downwardly and between ovens G G', thence downwardly and under ovens G' and 3, by duct 22, into the chimney.

R are dampers in the oven-walls of the dead-air spaces J J' J'', to admit hot air from the 50 spaces into ovens G, G², and 3 when desired. The door of the upper and lower ovens is hung to fall horizontally, and is supported in a shelf position by quadrant-rods 20, one end secured to near the outer corners of the door, 55 and passed through the wall of the range into spaces I J I' J', where their ends are provided with a counterbalance-weight, 21, to stop against the wall to sustain the door when open and to retain it closed when shut.

R' is a header-pipe connected to boiler 4 by 60 pipe R², and R³ are the distributing-pipes of the hot-water system to heat the building in which the range is placed, S being the return-pipes of the system entering the tubular header S', connecting with the dome of the boiler. 65

P is a hand-rail around the top edge of the range, and Q are doors to allow accumulated soot and ashes to be raked from under and between the ovens.

I claim as my invention—

1. A range-stove in which are combined two double ovens, G G' and G² G³, intermediate furnace, A, single oven 3, a hot-water-circulating boiler, 4, and intermediate furnace, A', arranged to form a rectangular block, the 75 ovens G G' separated from oven 3 by a space in which are diving-flues D D', common to both furnaces, and flue-spaces over, between, and under the ovens G G', and discharging through duct 22, under oven 3, and thence 80 through aperture 5 in the bottom of the range, whereby furnace A will more or less heat all the ovens when desired independently of the boiler, as set forth.

2. A range-stove in which are combined two 85 double ovens, G G' and G² G³, common to furnace A, boiler 4, and single oven 3, common to furnace A', said ovens and furnaces separated by dead-air spaces g, and diving-flues D D' D² D³, discharging between and under 90 the ovens into ducts 21 22, and thence through apertures 5 5' in the bottom of the range, the whole forming a rectangular block, as described.

3. In a range stove in which are combined 95 two double ovens separated by a furnace, A, a single oven, and a hot-water-circulating boiler, 4, separated by furnace A' and arranged to form a rectangular block, whereby one furnace will heat the two double ovens 100 and the bottom of single oven, and the other furnace the single oven and the hot-water boiler and discharge the smoke through apertures in the bottom of the range, as set forth.

4. In a range-stove in which are combined 105 two double ovens, a single oven, a hot-water-circulating boiler, and two furnaces, the boiler supported on a lining, 16, and heated by top flues, k, side flues, 28, and return-flue 8, under the boiler, and discharging by flue 17 into 110 aperture 5' in the bottom of the range, as set forth.

JOSEPH ROY.
